UNITED STATES PATENT OFFICE.

SAM EVERETT FINLEY, OF ATLANTA, GEORGIA.

APPARATUS FOR SPRAYING BINDING MEDIA ON ROADS.

1,397,045.

Specification of Letters Patent. Patented Nov. 15, 1921.

Application filed October 29, 1919. Serial No. 334,315.

To all whom it may concern:

Be it known that I, SAM E. FINLEY, residing at Atlanta, county of Fulton, State of Georgia, have invented certain new and useful Improvements in Apparatus for Spraying Binding Media on Roads; and I do hereby declare the following to be a full, clear, and exact description of the invention, such as will enable others skilled in the art to which it appertains to make and use the same.

The invention relates to machines for applying oil, tar, and the like, on roadways and has for its object to provide a simple and efficient mechanism, preferably in the form of an automobile vehicle, with means for applying the selected media in accurately regulated quantities to effect a thorough and efficient binding together of the road material and a smooth resilient wear resisting surface with a minimum expenditure of material and labor. To this end the apparatus is provided with a tank to contain the binding material, one or more auxiliary tanks to contain air under pressure adapted to be connected with the first mentioned tank to force the oil from the latter at any desired regulable pressure, a distributor header provided with spraying nozzles disposed at the rear of the machine and adapted to be adjusted laterally to spread the binding media uniformly and without over-laps and also adapted to be disposed laterally to one side of the machine, so that a strip of roadway extraneous the path of travel of the machine may be treated, without the surface of the roadway being marred or damaged by the passage of the machine thereover. These and other objects of the invention will appear from the following description in connection with the annexed drawings in which:

Figure 1 is a side elevation of the machine with certain obvious portions thereof omitted.

Fig. 2 is a rear elevation.

Fig. 3 is a similar view showing the distributor disposed at the rear and wholly to one side of the vehicle, and

Fig. 4 is a plan view of the piping system connecting the air compressor directly to a liquid containing tank and to the pressure tank arranged within said liquid containing tank.

In the application of oils, tars, and similar binding mediums to the surface of

streets, highways, and the like, whether the same be a lighter application primarily as a dust suppressor, or to effect the combined result of suppressing the dust and preserving the roadway, or the employment of heavier bituminous or asphaltic road binders in the construction of the road proper so as to provide a durable roadway, conditions are frequently such that to be successfully met the machine effecting the distribution of the binding material must have a wide range of adjustment, both as respects the quantity of binding medium applied and the particular adjustment or disposition of the distributing apparatus in applying the same. It is a well known fact that it is practically impossible to obtain uniform conditions as to materials and the disposition thereof in constructing a roadway so that even when substantially the same character of material is employed through a given road section one portion of the surface may be of a denser formation, while an adjacent section will be more open and porous and, obviously, where different materials are employed in the construction of adjacent road sections the conditions of compactness and porosity will be correspondingly more widely varied, so that different quantities of the binding medium must be applied to the structurally different road sections to effect the desired results in the most economical manner, namely, the production of a thoroughly bonded wear resisting surface, with a minimum quantity of binding medium. If it were attempted to apply the same quantity of binding material per unit surface to the entire roadway it is obvious that if such quantity is sufficient to properly bond a relatively compact road bed, it will be wholly insufficient when applied to a section in which the road material is more open or porous and conversely if the quantity of oil be regulated to produce the desired result on a highly porous road bed, say broken stone or gravel, such quantity would be greatly in excess of that needed to obtain the desired result where the road material is more densely and compactly applied and the excess of the binding medium would tend to run off the road surface or to collect in pools, and thereby either unnecessarily waste the binding medium or produce highly unsatisfactory conditions in the road surface.

The necessity of wide range of adjust-

ment of the distributing means for the binding medium becomes more compelling when the apparatus is employed to distribute the different types of binding material such as is the case where a priming coat of light material is first applied and later a finishing coat of relatively heavy binder, as the quantities per unit surface of the two materials would necessarily be radically different. Similar conditions would occur in the case of a relatively heavy binding medium applied to a road surface that has been worked up to the desired cross-section and grade with broken stone or the like of appropriate size, in which the quantity of the heavier product would be frequently three times as great as that of a lighter binding medium applied to the same type of construction as a seal or squeegee coat.

It is also apparent that the amount of binding material per unit surface of roadway will vary in accordance with the speed of travel of the distributing machine over the roadway and as this speed of travel is more or less variant, according to the condition of the road as to surface, grades and the power of the engine on the vehicle, it is evident that the distributing mechanism must be capable of ready adjustment and regulation to effect a proper uniform distribution of the binding medium under these conditions also.

It is also desirable that, inasmuch as the distributor cannot at all times travel in a definite path relative to the road boundaries, means be provided for taking care of the variation in the path of travel, no matter how slight such variation may be, because it is quite necessary in applying any of the various grades of binding material to avoid over-laps on the one hand, which means an excess of the binding medium at all such over-laps and also to prevent skips or untreated sections of the roadway, which would necessitate careful and individual hand treatment.

These various conditions are met in the present apparatus by providing the machine with means for maintaining a uniform but regulable pressure on the binding medium as it is delivered from the distributing apparatus so that regularity of distribution may be effected; and also by so constructing the distributing header or manifold that the latter may be quickly adjusted within reasonable limits transversely of the machine to compensate for any divergence of the latter from the normal line of travel in either direction and thereby preventing both over-lapping of the adjacent treated sections on one hand and skips or untreated sections of the road surface on the other.

A further condition to be met in the practical treatment of roadways, especially with relatively heavy or durable binding medium,

in which the vehicle should not travel over the road surface immediately in advance of the spraying mechanism, when the wheels of the vehicle would be liable to rut or displace the material of the road bed, which could not be readily worked back to proper surface or grade after the application of the binder because of the relatively quick setting of the latter, is to provide the machine with a manifold or distributor capable of being adjusted wholly to one side of the machine, and normal to the direction of travel of the latter so that the vehicle travels over a portion of the roadway entirely outside of the area of distribution of the binder. With this arrangement, which constitutes an important element of the present invention, it is feasible to treat successive sections of a roadway while preserving each section so treated at its normal surface or grade so that an even uniform application of the binding medium may be effected without a possibility of the material collecting in pools or running off the surface.

In treating roadways with heavier grades of binder it is always necessary to apply artificial heat to the binding medium in order to render the same sufficiently fluid to be sprayed uniformly from the nozzles and if for any reason, as by stoppage of the machine, the binding medium tends to cool in any part of the conductive system between the tank and the distributing nozzles it will congeal and obstruct the various nozzles, particularly the nozzle outlets, by the action generally known as "freezing" and a good distribution cannot be subsequently obtained until after the obstructing material has been again reduced to the necessary condition of fluidity. Means have been made to overcome this difficulty by providing a connection from the exhaust of the engine which drives the vehicle to the distributor manifold or spray header so that when the binding medium freezes in the distributor, the hot exhaust gases from the engine may be forced through the header to heat the congealed material and allow the same to drain out of the entire header system.

It will, therefore, be seen that the present invention is designed to meet the most exacting conditions of road treatment with all types of binding material from the lightest to the heaviest and to apply the same in accurately regulated minimum quantities per surface square yard ranging from one-eighth to one-fourth of a gallon for light oils or tars up to a maximum of from one and a half gallons to two gallons per surface square yard on highly porous broken stone or gravel road surfaces, and at the same time assuring uniformity of distribution.

Referring to the accompanying drawings, 1 indicates the chassis of an automobile vehicle provided with wheels 2 and 3, the former of which are driven by the usual internal combustion engine, not shown. Suitably mounted on the chassis 1 is a tank divided into chambers 10 and 11, by means of a transverse partition 11', the former forming a receptacle for the binding material and the latter an air tank for containing air under relatively heavy pressure, which is ultimately to be delivered into the chamber 10 to force the binding material therefrom and into the distributing header, by means of which the material is forced, in the form of conical sprays, on to the road surface.

Located laterally of the main tank are auxiliary pressure tanks 50 and 51 which are also adapted to retain air under relatively heavy pressure and to deliver the same as may be desired to the oil receptacle 10. Preferably the pressure of the air in the several tanks 11, 50 and 51 is maintained at a point much higher than that required to force the binding material from the tank 10 and through the spray nozzles in the desired amounts to effect an even distribution, and the necessary pressure is maintained in all or any of the tanks or receptacles by means of an air compressor 52 mounted on the chassis, in advance of the main tank, and driven from a shaft 4 which may be either the main shaft between the engine and the transmission, or a jack shaft suitably coupled thereto. As shown, the shaft 4 is provided with a clutch consisting of a fixed member 57 and a loose member 56 which are brought into engagement by a suitable lever mechanism 58 when the compressor 52 is to be operated. The clutch section 56 is provided with a sprocket gear 54 which is connected by a drive chain 53 with a sprocket wheel 55 on the shaft of the compressor. The outlet side of the compressor 52 is connected by pipe 60 with a piping system delivering the air either directly to the tank section 10 or to the compressed air chamber 11 of the tank and said pipe 60 is provided with an ordinary stop valve 61 and a check valve 62, beyond which branch pipe 63 connects at 63' to pressure chamber 11 and branch 65 is connected to the upper portion of the dome 12 of the main chamber with the pressure regulator 66 interposed to accurately regulate and fix the air pressure admitted to the section 10 of the tank which contains the road treating medium. Between the pressure regulator 66 and the connection between the pipe 65 and the dome 12 is a check valve 67 which is effective to prevent any gases or liquid material passing backward from the tank section 10 to impair the efficiency of the pressure regulator. The coupling between pipe sections 63 and 65

is provided with a stop valve 64. The discharge pipe from the compressor 52 is also connected with the auxiliary air tanks 50 and 51 by means of flexible pipe sections 60' and detachable coupling members 61' so that the auxiliary tanks 50 and 51 may be charged simultaneously with the air chamber 11 of the main tank, or may be shut off or disconnected at will.

The auxiliary tanks 50 and 51 are connected by cross pipe 62' provided with stop valves 64' and 65' on opposite sides of a connected pipe 66' provided with a stop valve 67', which latter pipe is connected to the top of the dome 12 and is provided with pressure regulator 68 and a check valve 69, which latter serves the same purpose as check valve 67 in preventing volatilized or liquid material from the tank section 10 passing upward into the pressure regulator 66. An over-flow pipe 70 provided with a suitable stop valve 71 is connected to the dome 12 to permit discharge of accumulated pressure in the tank when the latter is being filled with road material and also to permit the escape of any excess of the binding material when the proper level in the tank section 10 has been reached.

With the described arrangement of the compressor and air tanks it will be apparent that the necessary and properly regulated pressure may be applied to the surface of the binding material in tank section 10 from any or all of the air reservoirs 11, 50 and 51, or if desired, directly from the compressor. For example, when it is found desirable to supply air from the compressor 52 alone directly to the tank section 10, valves 61 and 64 are opened and valves 64' and 65' are closed, thereby causing the air from compressor 52 to pass by way of pipes 60, 65, through pressure regulator 66 into the upper part of dome 12. At the same time any excess air supplied by the compressor is delivered by pipe 63 to the auxiliary chamber 11 wherein it is held in reserve should the air pressure be delivered by the compressor 52 fall below the necessary point for any reason. When it is found necessary or desirable to use the compressed air in tanks 50 and 51 the valves 64', 65' and 67', are open, thereby admitting pressure from both of said tanks 50 and 51, by way of cross pipe 62' and vertical pipe 66' to the upper portion of the dome 12, the pressure equalizer or reducing valve 68 serving to admit the desired working pressure to the tank section 10. If it is desired to use the air pressure from one of the tanks 50 or 51 only the appropriate valve 64' or 65' is closed. The several air tanks and the main tank are provided with suitable pressure gages and stop valves to indicate the desired pressure and also to prevent over-charging.

This arrangement admits of an exactly 130

predetermined and uniform pressure to be maintained on the material in the tank section 10 to insure the uniform distribution of the material from the spray nozzles of the distributor head, and thereby effect a properly regulable distribution of the binding material to the road surface, and as this pressure is supplied from any one of the series of air tanks or receptacles, which in turn are kept charged to a pressure largely in excess of that normally required in the tank section 10, it will be seen that any desired pressure in the tank section 10 may be obtained and maintained, without variation, such as would be produced by pulsations of the compressor, by a proper adjustment of the pressure regulators or equalizer valves 66 and 68.

Connected to the bottom of the tank section 10 is the outlet pipe 14 provided with a stop valve 15 to the lower end of which pipe 14 is connected a drain valve 16 and a horizontal pipe 17 which latter is provided at its rear end with a stop valve 17' and a coupling member 18. A vertical pipe section 19 is coupled to pipe 17 and a horizontal pipe 21 disposed transversely of the rear portion of the vehicle frame, and said pipe 19 is provided with a stop valve 20. Secured to the horizontal frame members of the chassis are two angle bars 1', 1' which extend rearwardly of the chassis and serve as supports for two yoke members 25, 25, which are connected by a bridge piece 31, so that said yokes and bridge piece are capable of longitudinal movement along the angle bars 1', 1'. Slidably mounted in the yokes 25, 25 is a header support 26 generally tubular in cross section and having an intermediate rack section 27, in which support 26 the pipe 21 is secured so that said pipe 21 partakes of any lateral movement of the support.

Mounted on the bridge piece 31 is a housing piece 30 in which is journaled a vertical shaft 29, on the lower end of which is mounted a pinion 28 meshing with the rack 27 carried by the support 26, so that when said shaft 29 is rotated by the means of the hand wheel on the upper end thereof, the support 26 is moved to the right or left according to the direction of the rotation of said shaft, thereby moving pipe 21 transversely of the machine to a corresponding extent. Each section of the pipe 21 adjacent the connection thereof with pipe 19 is provided with a cut-off valve indicated at 24 and 24' respectively, so that the material delivered from the tank section 10 may be directed toward both ends of the pipe 21 or toward one end only, accordingly as both or only one of the valves 24 and 24' are open or closed.

The outer ends of the pipe 21 are provided with T couplings 22 having plug caps in the outer ends thereof and having short

pipe sections 23 connected to the downwardly extending branches. The lower ends of the short pipe sections 23, 23 are screw threaded to engage detachable unions or couplings 43 and 44 respectively, which in turn are connected with vertical pipe sections 41 and 42, each of which is in turn connected with a horizontal T coupling 49. Connected to the respective couplings 49 are two horizontal parallel pipe sections 45 and 47 which have disposed longitudinally thereof a series of T couplings or unions 40 to which are connected suitable nozzles 46 and 48 for delivering conical jets or sprays in a vertical direction. The couplings 40 and the connected nozzles are disposed in staggered relation on the respective header pipes 45 and 47 and the latter are disposed at such an elevation above the ground that the conical sprays or jets of the binding material delivered by the several nozzles are successively contiguous when they reach the ground but do not materially over-lap, so that the binding material is applied to the road surface as an even uniform layer.

In the normal operation of the machine, the distributor occupies the position shown in Fig. 2 with the jet nozzles disposed equally on both sides of a vertical median line of the machine so that the road treating material will be distributed in a uniform sheet directly behind the machine having a width equal to the lateral range of the outer sprays on each end of the distributing header. In turning curves in roadways and in avoiding obstructions it is desirable that the distribution of the oil in a lateral direction be varied and this operation is effected by rotating the shaft 29 in the appropriate direction which moves the carrier 26 and the entire header to the right or left, according to the direction of rotation of said shaft 29. An operator standing on the rear of the machine and observing the distribution of the oil on the road surface by the jet nozzles, by appropriately moving the header to the right or left, through the agency of shaft 29 and carrier 26, may quickly adjust the header laterally in either direction and to any extent up to the limits of movement of the carrier 26, so that the outer marginal edge of the layer or coating of oil may be made to follow any desired path, so as to conform to the prescribed lateral limit of the roadway, to avoid obstructions or portions of the roadway not to be treated and also to conform to the meeting edge or lateral limit of an adjacent strip or stretch of roadway already treated without overlapping. The lateral movement of the header and its support is rendered possible by reason of the flexibility of the pipe joints below the valve 15 in the outlet connection of the tank section 10 and as the yokes 25 slide

freely on the angle bars 1', the lateral adjustment of the header may be effected without undue strain on the mechanism.

When the spraying operation is suspended 5 for any length of time, if the road treating material is of a character required to be heated to reduce it to the necessary degree of fluidity, it tends to freeze or congeal in the header manifold and the connections between the same and the tank, thereby rendering 10 it difficult to start the machine again without first clearing the header and its connections of the congealed material. In order to avoid this objectionable feature provision is made for connecting the header 15 with the exhaust of the engine which drives the vehicle. To accomplish this and also to prevent connection between the header and the engine exhaust when the machine is spraying, the header is adapted to be swung 20 rearwardly and upwardly until the pipe 45 is engaged by hooks 80 pivoted to the rear end of the angle bars 1', said swinging action being effected at the T couplings 22 which support the header from the ends of 25 pipe 21. The T coupling 22 adjacent the rear end of the exhaust from the engine is provided with an angularly disposed coupling 82 having a stop valve 81 associated therewith, which coupling is adapted to be 30 engaged with the mating coupling member 83 on the end of a flexible pipe section 84 attached to the discharge end of the exhaust pipe 7 of the engine, so that when the header 35 is swung up into engagement with the hooks 80 the coupling member 82 is in position to be engaged by the coupling member 83 on the end of the exhaust pipe. After this coupling is effected the hot gases of the exhaust 40 traverse the header and its various connections and prevent the road treating material from congealing and ultimately forces such material as may remain in the header and its connections out of the jet nozzles, so 45 that the header will be free of all obstructions and ready for subsequent use. In order to prevent the possibility of connecting up the oil supply with the header while the exhaust connection from the engine is coupled 50 to the header it will be noted that before the header can be swung to its lower operative position connection between the engine exhaust and the header at coupling 82 and 83 must be broken. This arrangement is 55 found necessary and desirable inasmuch as a careless attendant might leave the valve 81 open when the header is swung to operative position, thereby permitting the road treating material to be forced into the engine 60 through the exhaust connections. By disposing the coupling member 82 in such relation that the header cannot be swung into operative position until the connection at 82 with the exhaust pipe is broken, this 65 danger is entirely obviated and even if the

valve 81 is accidentally left open no more serious result than the wastage of a little of the road binding material would ensue.

Under certain conditions it is found desirable, if not imperative, to apply the binding material to the surface of a road which has not been traversed by the wheels of the machine, as the latter would tend to mar and rut the surface under certain circumstances, such as are pointed out in my companion application filed concurrently herewith, Patent No. 1,341,458, granted May 25, 1920, and to adapt the present machine to such an operation the header is so constructed as to permit its application and disposition wholly to one side of the machine 75 without, however, interfering with the normal lateral adjustments of the header as hereinbefore explained.

The particular means for effecting this result are illustrated in Fig. 3, in which the header is shown as being disconnected from the left end pipe section 23 and rotated through 180 degrees on the right end pipe section 23 and an auxiliary pipe section 90 90 connected to the right end T coupling 22, said auxiliary pipe section having an outer angle coupling 91 with a short vertical pipe section 92 adapted to be connected with coupling 44 to pipe section 42 at the extreme 95 outer end of the header. A suitable tie rod 93 connected to the coupling 91 and to a bracket 35 on the support 26 serves to brace and support the header in the outboard position shown. It will be noted that with this 100 disposition of the header the distribution of the binding material to the road surface is entirely outside of the line of travel of the vehicle wheels so that said material is applied to the smooth unbroken surface of the 105 road.

When the header is adjusted laterally of the machine as shown in Fig. 3, the supply of road treating material from the tank 10' is delivered through the right end section 110 of pipe 21 and the opposite section of said pipe is cut off at valve 24. When it is desired to dispose the header on the opposite side of the machine the same mode of procedure is followed as heretofore described, except 115 that the header is swung on the left hand T coupling 22 as a pivot, after the right end of the header has been disconnected at coupling 43. Pipe section 90 is then connected to the left end coupling 22 and the outer end 120 of the header as before. When so arranged the header will distribute oil laterally of and to the left of the machine. When it is desired to move the header back to its normal position at the rear of the machine auxiliary 125 pipe section 90 is disconnected and the header swung on left end T coupling 22 as a pivot until the coupling member 44 comes opposite the right end pipe section 23 when the coupling operation is effected and the header is 130

then in proper position disposed transversely of the rear of the machine. It will be particularly noted that the lateral adjustment of the header by means of the gear and rack 5 27 and 28 is possible for any of the three dispositions of the header, namely, at the rear of the machine or laterally and to the left or right thereof, for the reason that the header is supported in the carrier 26 at all 0 times and moves with the latter.

From the foregoing it will be apparent that the machine possesses a wide range of adaptability to meet substantially every condition in road treatment with oils, tars, and 15 the like, and is well adapted to the application of a uniform distribution of the road treating materials exactly where the same are needed and because of the accurate control of the uniform pressure applied to the 20 binding material and the ready adjustability of the header, the application of the binding medium of the road surface may be effected with practically mathematical precision, both 25 as to the quantity of material per unit of road surface and also as to the exact superficial road surface to be covered, the boundaries of which may be followed with great accuracy by appropriately adjusting the header by means of hand wheel shaft 29, as 30 hereinbefore described.

When it is desired to fill the tank with the road treating material the valve 71 in the over-flow pipe 70 is opened to permit the accumulated air pressure to escape, the valve 35 20 in the supply piping from the tank to the header system is closed and a connection to the source of supply of the material is made at the coupling 18 on the end of pipe 17 so that the material may be delivered either 40 by gravity or by suitable pressure apparatus into the tank, and when the desired amount of material has been admitted to the tank the valves 71 and 17' are closed and the connection to the source of supply broken 45 at coupling 18. The vehicle is then transported to the place of application of the road material and meanwhile the requisite amount of air pressure is admitted to the tank section 10 and the apparatus is ready 50 for operation, after the header has been disconnected from hooks 80 and swung to its normal vertical position, as hereinbefore explained.

What I claim is:

55 1. A distributor for bituminous road binders in heated form comprising a vehicle, a liquid tank thereon, a spray header at the rear of the vehicle connected with said tank, an air compressor on the vehicle, an air tank 60 interposed between the liquid tank and the compressor, an automatic pressure regulator in the connection between the air tank and the liquid tank, and means to prevent back flow toward the pressure regulator 65 from the liquid tank.

2. A distributor for bituminous road binders in heated form comprising a vehicle, a liquid tank thereon, a spray header at the rear of the vehicle connected with said tank, an air compressor on the vehicle, an air tank 70 interposed between the liquid tank and the compressor, an automatic pressure regulator in the connection between the air tank and the liquid tank, and a check valve between the liquid tank and the pressure regulator to prevent back flow from the liquid tank. 75

3. A distributor for bituminous road binders in heated form comprising a vehicle, a liquid tank thereon, a source of compressed air, and connections between said source and the liquid tank, said connections including an automatic pressure regulator and a check valve between the latter and the tank, whereby uniform air pressure is maintained 80 in said tank, and back flow therefrom prevented. 85

4. A distributor for bituminous road binders in heated form comprising a vehicle, a tank thereon having a liquid compartment 90 and an air compartment, an air compressor connected to said air compartment, a separate air tank connected to said compressor, and connections including an automatic pressure regulator and a check valve between the liquid tank and the air compartment and between the liquid tank and the separate air tank respectively, each check valve being located between the liquid tank 95 and a corresponding pressure regulator. 100

5. A distributor for liquid road material comprising a vehicle, a liquid tank thereon, yokes slidably mounted on the rear of the vehicle frame, a hollow carrier slidably mounted in said yokes for adjustment transversely of the machine, a rack section on said carrier, a shaft having a pinion engaging said rack, and a nozzled header system fixed to said carrier and connected with the liquid tank. 105

6. A distributor for liquid road material comprising a vehicle, a liquid tank thereon, yokes slidably mounted on the rear of the vehicle frame, a hollow carrier slidably mounted in said yokes for adjustment transversely of the machine, a rack section on said carrier, a shaft having a pinion engaging said rack, a pipe mounted in said carrier and connected to the liquid tank, a nozzled header disposed below and substantially parallel with the carrier, and intermediate pipe sections connecting the pipe and header at each end. 110

7. A header system for road treating vehicles comprising a horizontal support 125 mounted transversely of the vehicle, means for moving said support in the direction of its length, a supply pipe fixed in said support, vertical pipes having intermediate detachable joints depending from said sup- 130

ply pipe, and a nozzled header pipe connected to the lower ends of said vertical pipes.

8. A header system for road treating vehicles comprising a horizontal support 5 mounted transversely of the vehicle, means for moving said support in the direction of its length, a supply pipe fixed in said support, vertical pipes having intermediate detachable joints depending from said supply 10 pipe, and parallel nozzled header pipes connected to the lower ends of said vertical pipes.

9. A header system for road treating vehicles comprising a horizontal support 15 mounted transversely of the vehicle, means for moving said support in the direction of its length, a supply pipe fixed in said support, vertical pipes having intermediate detachable joints depending from said supply 20 pipe, parallel header pipes connected to the lower ends of said vertical pipes, and spray nozzles disposed longitudinally of said header pipes, the nozzles of the respective pipes being disposed in staggered relation.

10. A header system for road treating vehicles comprising a horizontal supply pipe disposed transversely of the machine, a nozzled header pipe detachably connected at each 25 end of the supply pipe and adapted to be disconnected at either end and swung laterally to either side of the vehicle upon one or the other of the connections, and an auxiliary pipe adapted to be connected to the 30 end of the supply pipe and the outboard end of the header pipe when the latter has been swung to a lateral position.

11. A header system for road treating vehicles comprising a horizontal supply pipe disposed transversely of the machine, a nozzled header pipe detachably connected at each 40 end of the supply pipe and adapted to be disconnected at either end and swung laterally to either side of the vehicle upon one or the other of the connections, an auxiliary pipe adapted to be connected to the 45 end of the supply pipe and the outboard end of the header pipe when the latter has been swung to a lateral position, and a tie rod supporting the outer end of the header 50 pipe.

12. A header system for road treating vehicles comprising a horizontal support mounted transversely of the vehicle, means for moving said support longitudinally, a supply pipe fixed in said support, a nozzled 55 header pipe detachably connected to each end of the supply pipe and adapted to be

disconnected at either end and swung laterally to either side of the vehicle upon one or the other of the connections, and an auxiliary pipe adapted to be connected at the end of the supply pipe and the outer end of the header pipe when the latter has been swung to a lateral position.

13. A header system for road treating vehicles comprising a horizontal support mounted transversely of the vehicle, means for moving said support longitudinally, a supply pipe fixed in said support, a nozzled header pipe detachably connected to each 60 end of the supply pipe and adapted to be disconnected at either end and swung laterally to either side of the vehicle upon one or the other of the connections, an auxiliary pipe adapted to be connected at the end of the supply pipe and the outer end of the header pipe when the latter has been swung to a lateral position, a bracket mounted on the support, and a tie rod connecting the bracket and the outer end of the auxiliary 65 pipe.

14. A distributor for liquid road material comprising an internal combustion engine propelled vehicle, a liquid tank thereon, a nozzled header pivotally connected with said vehicle and adapted to be swung upward and backward from operative position, a valved connection between the header and the tank, a valved coupling member on the pivoting section of the header, and a mating coupling member on the engine exhaust pipe, said coupling members being adapted 70 to be engaged only when the header is swung to inoperative position, whereby the exhaust from the engine will be directed 75 through the header to prevent congealing of the liquid when the header is in inoperative position.

15. A distributor for liquid road material comprising a vehicle, a liquid tank thereon, a nozzled header connected with said tank, means for supporting the header at one side of the vehicle and wholly lateral to the path of travel, whereby the material will be sprayed only on a strip of road wholly extraneous of said path of travel, and means for adjusting the header in the direction of its length.

In testimony whereof I affix my signature, in presence of two witnesses.

SAM EVERETT FINLEY.
